UNITED STATES PATENT OFFICE.

ARTHUR B. CAMPBELL AND IRVING L. BROWNELL, OF ORLAND, CALIFORNIA.

RADIATOR.

Application filed February 11, 1924. Serial No. 692,104.

This invention relates to heat radiators as used to warm rooms in buildings and particularly to such radiators wherein water is the convection fluid used to carry the heat to the walls of the radiator and wherein the water is heated by an electrical heating element.

The objects of our invention are to provide a radiator of the type outlined which will represent the utmost in simplicity combined with effectiveness—also a device easily contrived from the existing parts of common hot water or steam radiators as now found in buildings and whereby the same may be changed to electrically heated radiator units and with consequent elimination of the present cellar furnaces and boilers, and the change made without mechanically altering the existing radiator proper or moving it from its original position.

We achieve the desirable objects outlined by the apparatus shown in the accompanying drawings and in which:

Figure 1 is a side elevation showing our improved radiator as it would appear installed;

Figure 2 is an end elevation of the radiator as seen in Figure 1;

Figure 3 is an enlarged perspective view showing the general appearance of the electrical heating unit; and

Figure 4 is an enlarged perspective view of one of the vented plugs for the expansion pipe.

In the figures, (1) represents a standard hot water or steam radiator of vertical tubular members connected in the usual way through the upper and lower ends.

In one of the outlets of the lower end is screwed an electrical heating unit (2) and at the opposite lower end a drain cock (3).

The electrical heating unit may be of any standard construction, with preference given to a form having an extended tube (4) containing the resistance elements and having a threaded flange (5) by means of which it may be screwed to the usual pipe inlet of the radiator and will then extend as shown, past several of the vertical tubular members.

In large radiators the electrical heating unit may extend the full length of the

radiator assembly or a separate one inserted from opposite ends if desired.

The winding of the heating unit is a matter apart from this invention, but the type of winding with a switch (6) for throwing in one or more sections, and a suitable thermostat (7) for breaking the circuit upon excessive heat is preferred.

From the heating unit, wires (13) extend to any suitable source of electrical energy.

To the two upper end members of the radiator assembly is secured a relatively large pipe (8) lying horizontally across the upper ends of the members. This pipe is for expansion of the water in heating, also to provide vents at opposite ends of the heater, and also to provide openings for filling the radiator with water.

At opposite ends of the pipe are T's (9) each with a pipe plug (10) loosely screwed in place. The pipe plugs are each vented with a small hole (11) as best shown in Figure 4.

The expansion pipe (8) is spaced above the radiator proper by the two short pipes (12) as shown, and forms an additional radiator element heated by the slight amount of steam which finds its way in the pipe to condense and run back into the lower members.

At the right hand upper end we arrange a sight water level gage tube (14) tapped into the upper T (9) and lower L (15) as shown. This gage tube extends from below the upper edge of the radiator to a point above the upper edge, thereby making it an easy matter to determine when the radiator is full, the desired operative condition of the device being with the radiator entirely filled and the pipe (8) substantially free of water to function as before mentioned.

The drain cock (3) is for drawing off water when not in use during long warm periods, or for drawing off hot water for any use.

To fill the radiator with water, one of the vented plugs (10) is removed and water poured in the pipe, while the other vented plug prevents blowing back of the contained air.

Having thus described our invention, it will be seen to effect the desired objectives in a simple effective manner and it is just this simple manner of arranging the apparatus with manifest variations that we wish to cover in our appended claim.

We claim:

A radiator of the character described comprising a series of vertically arranged tubular members, a header connecting the upper ends of said members, a header con-

nected to the lower ends of said members, means for applying heat thereto at the lower ends of the members, an expansion pipe above and parallel to said upper header, pipes connecting the ends of the expansion pipe with the tubular end members, and filling and vent plugs on each end of the expansion pipe.
